UNITED STATES PATENT OFFICE.

ADOLPHE A. CHAILLET, OF SHELBY, OHIO, ASSIGNOR TO THE SHELBY ELECTRIC COMPANY, OF SAME PLACE.

DESIGN FOR A FILAMENT FOR INCANDESCENT ELECTRIC LAMPS.

SPECIFICATION forming part of Design No. 33,481, dated October 23, 1900.

Application filed June 11, 1900. Serial No. 19,964. Term of patent 14 years.

To all whom it may concern:

Be it known that I, ADOLPHE A. CHAILLET, a citizen of the Republic of France, residing at Shelby, in the county of Richland and State of Ohio, have invented and produced a new and original Design for an Incandescent-Electric-Lamp Filament, of which the following is a specification, reference being had to the accompanying drawings, forming part thereof.

In the drawings, Figures 1, 2, and 3 are side elevations of the filament; and Fig. 4 is a plan, the various elevations being taken from correspondingly-numbered arrows about Fig. 4.

The leading or material features of my design consist of a filament having its extreme ends comparatively near each other, the filament then flaring in substantially straight lines therefrom and such straight lines being connected by a series of substantially elliptical loops, the major axis of which is transverse to the plane bisecting the angle which the straight portions of the filament make. The said substantially straight portions connect with the opposite ends of the outside

ellipses, merging therewith at the end of the major axis.

Referring to the parts by letters, A represents the filament, a the substantially straight sides, and a' the series of transverse elliptical loops. These loops appear in alinement in Fig. 3 and overlapping in Fig. 1 and very much foreshortened in Fig. 2; but, as will be seen, the major axis is at substantially right angles to the longitudinal bisecting plane, and this constitutes an essential feature of my design.

Having described my invention, what I claim as new, and desire to secure by Letters Patent, is—

The design for a filament for incandescent electric lamps, substantially as herein shown and described.

In testimony whereof I hereunto affix my signature in the presence of two witnesses. 45

ADOLPHE A. CHAILLET.
